APPARATUS FOR DRYING AND
HEAT-TREATING

Adam J. Kisskalt, Grosse Pointe Farms, Mich.

Application May 9, 1946, Serial No. 668,574

3 Claims. (Cl. 22—87)

1

This invention relates to the heating and drying of various kinds of work including metallic work pieces, molds, ladles, and the like, and it has to do particularly with a portable sectionalized heating and drying apparatus adapted to treat the work pieces in containers or flasks or the like.

The metallic work pieces may be such items as dies, or castings, or sheet steel and other work or items which are to be dried, such as sand molds, or plaster molds, or ladles for molten metal which are lined with brick or other ceramic material. In disclosing the invention, it is convenient to make reference largely to molds.

The prevailing method of drying sand molds, for example, for foundry purposes, is to place the molds in an oven and heat the molds and flasks. This oven method of drying the sand molds, while resulting in little waste due to improper drying, is expensive and inconvenient. The ovens are large and require much floor space. If an oven is loaded with a diversity of molds, some of which are small and some of which are large, some of them remain in the oven longer than is necessary. This results in loss of time and heat. Moreover, the entire mold and flask structure must be heated all the way through, thus representing another uneconomical use of heat. Then too, considerable space is required for accommodating the molds after removal from the oven and while they are cooling. Metal flasks are necessary for the oven drying process and frequently delays for special jobs are necessary until the flasks are procured. Inasmuch as the ovens are of large construction and are in fixed position, considerable handling and movement of the work is necessary thus resulting in an excess of labor and an ever present hazard of damage to the finished mold in its handling before and after it has been dried in the oven.

In the case of very large molds or pit molds, which cannot be moved to an oven, they are usually superficially or skin dried by the application of hand torches, gas flames, charcoal pots, or other means and with molds thus dried, the pouring must be done within a very short time and the danger always exists of ruining the casting by the reason of an imperfectly dried mold.

The present invention aims to provide an improved apparatus of a portable and sectionalized character for the heat treating of various work in containers of one kind or another, or the container itself, as in the case of a ladle, and an improved method of drying a work piece such as a sand mold or a plaster mold or ladle.

2

In accordance with the present invention, considering now a single drying unit, the apparatus resides basically in a cover applicable to the container to thus form an enclosed chamber. The unit is equipped with suitable heating means and means for circulating air in the chamber. The chamber being closed, the volume of air circulated is relatively small and is given a temperature high enough for the substance to be dried or heated. In other words, the gas within the chamber is re-circulated as distinguished from the passing a current of air over the work and then exhausting or venting the air. The chamber, however, is not sealed so that the vaporized products may escape therefrom due to the pressure developed. Suitable means such as directors or nozzles are employed where the nature of the work requires same and these are preferably adjustable to adapt the unit to molds or other work of different types and shapes.

Preferably, the individual unit is constructed so that it may be detachably connected to other like units. Accordingly, where a large container is encountered or a large heater or cover is desired two or more of the units may be connected together for joint operation.

Other objects of the invention will become apparent as the following detailed description is considered and one form of structure for carrying out the invention is disclosed in the accompanying drawings:

Fig. 1 is a view in the nature of a plan view with parts cut away to show the underlying structure.

Fig. 2 is a view partly in side elevation and partly in section showing one of the units.

Fig. 3 is an enlarged sectional view taken substantially on line 3—3 of Fig. 1 showing a structural feature.

Fig. 4 is an enlarged partial elevational view showing structural features.

Fig. 5 is a detailed view in section showing a nozzle or air directing means.

Fig. 6 is a sectional view taken substantially on line 6—6 of Fig. 1 illustrating the electrical connection for an electric motor.

Fig. 7 is a detailed view of enlarged nature taken on line 7—7 of Fig. 1.

Fig. 8 is an enameled schematic view showing four units assembled together.

Fig. 9 is a diagrammatic view illustrating how the drying process for molds may be carried out.

Fig. 10 is a side elevational view of a system shown in Fig. 9.

Fig. 11 is an elevational view of the lower por-

tion of the unit showing the structure for detachably connecting the units together.

Fig. 12 is a sectional view illustrating a single unit applied to a ladle for use with molten metal.

Fig. 13 is a view showing a single unit applied to a container with a metallic work piece therein.

As above set forth the invention will be described in detail with reference to the treatment of molds.

As shown particularly in Figs. 1 and 2, each drying unit comprises a suitable body or housing 1, the upper portion of which may be suitably reinforced by partitions 2 and mounted in the upper portion thereof, preferably in a central location, is an electric motor 3. The walls of the upper portion may be provided with openings 4 so that the same may be engaged by suitable means for lifting the same by machine or hand. There is a partition wall of suitable metal 6 extending across each unit and dividing it into upper and lower portions, said wall having a passage therethrough as at 7, for the shaft of the motor, as indicated. A second wall 8 spaced from the wall 6 has a surrounding wall structure 9 and the space between the walls 6, 8 and 9 is preferably insulated by suitable insulating material 10. This structure forms a lower cavity 11 in which is mounted a suitable fan or air propelling means 15. As shown herein this fan is of the radial flow type which takes air in its central portion and blows it out laterally although other types of fans may be used. The fan is centrally located preferably in the chamber 11 and surrounding the fan are suitable heating means here shown as electrical resistance elements 16 mounted upon suitable insulators 17.

The chamber 11 is defined by a partition 20 which is spaced from the wall 8 and underlies the fan and heating elements and this partition has a central opening 21 which aligns with the center part of the fan 15. The partition 20 is provided with suitable air outlet, or perhaps it would be more fitting to specify gas outlets, which are arranged to direct flow of gas or air and which may be termed nozzles and which are shown at 22. As illustrated in Fig. 9 each nozzle may be provided with a flange 23 held by a ring 24. The nozzles being inclined, as indicated, may be rotatably adjusted for directing the air. The nozzles are not necessary with some classes of work.

A single unit is designed to rest upon the flask 25 within which is the mold 26, and when resting in this position an interior enclosed chamber 27 is provided which communicates with the chamber 11 through the opening 21 and nozzles 22.

The lower edge portion of each unit is preferably reinforced as by means of an angle iron strip 30 and this strip is provided with a button which may be in the nature of a rivet head 31, one adjacent each end thereof. Also, the wall of the unit adjacent its lower portion is provided with key hole slots 32. It will be noted by reference to Fig. 4 that the button and key hole slots at opposite sides are reversed as to position. Therefore, when two units are to be assembled together the buttons 31 on one unit may slip into and connect with the key hole slots of the other. This is shown in Fig. 8. Also, where necessary, an outwardly extending flange such as the angle strip 33 may be applied to the lower edge of a unit as shown in Figs. 3 and 4. These reinforcing members are provided with

laterally extending key hole slots 35 for fitting over the buttons 31. When two or more units are secured together they may be bolted together at their upper edges for which purpose the side walls are provided with apertures 34.

It will be understood that two, three or more units may be thus united to cover molds of different sizes. In Fig. 8, for example, four units are indicated connected together to form a square area. If the mold is long, two, three or more units may be placed in a line.

Each unit is, of course, equipped with suitable means for the reception of electrical conductors for providing power for the heating element 16 and for the motor. A socket for this purpose is generally illustrated at 40. As shown in Fig. 6, conductors 41 may be passed through the insulation 10 and out through the partition 6 as by means of a bushing 42 for supplying current to the motor.

An expedient manner of use is illustrated in Figs. 9 and 10 where the work comprising the molds for example, as indicated at W, is caused to travel in the path as shown on a conveyer and the units travel in a closed path suspended from a track 44, one end of which is elevated as at 45. As a work piece approaches a unit moves down to the lower portion of the track 44 and rests upon the mold throughout most of the travel and around the curve 46 and as the combined unit and work reaches about the point x, the unit elevates to the higher portion of the track. The molds are thus dried in a continuous fashion.

In considering the drying of a mold, it may be assumed that a single unit is rested upon the flask, after the manner shown in Fig. 2, and the motor 3 set into operation and the heating elements 16 energized. The fan draws air (gas) in axially through the opening 21 and discharges the same in a heated condition radially into the outer regions of the compartment 11 from where the flow is directed by the nozzles 22 against the material of the mold. It is convenient to use electrical heaters as this makes the unit more easily handled although other heating means such as oil or gas burners may be used. However, the saving of time and labor in using electricity is to be taken into consideration and with this saving the use of electricity is economically feasible.

The air is thus circulated with a high velocity and is caused to penetrate into the deep pockets and recesses in the mold. To this end the nozzles may be adjusted to properly direct the air. The mold is speedily and efficiently heated and dried, this action being aided by the fact that the mold is completely covered by the drier thus retaining a maximum amount of heat. The air (gas) volume is maintained at a minimum thus facilitating the attaining of high temperature, a maximum number of air changes with a given fan which promotes rapid heat transfer and the volatile substances in the material are converted to steam vapor. The steam vapor is a good heat transfer medium and penetrates into the voids and recesses in the material and gives up heat to the deeper layers thereof thus progressively and rapidly heating up the mold. Accordingly, the mold material is dried in its innermost recesses with a minimum of superficial or case hardening and drying. Such superficial drying and hardening may result in cracks on the face of the mold.

As the volatile substances are evaporated the

same may readily escape because the combined chamber 11 and 27 is tight but not sealed and the escape of the gases may readily occur at the joint where the unit rests upon the container. Thus, the process may be visualized as one wherein steam vapor is produced by the heat and which is permitted to escape from the chamber as it is developed. Of course, the length of time it takes to dry a mold or heat other work depends upon the size of the work, the depth to which the substance is to be dried or heated and other factors. This can be regulated by those practicing the invention in a manner best calculated to produce the desired results for the work in question. This may vary also with the form and shape of the work, having in mind that some may have rather deep cavities therein and others may be relatively flat in form with relatively small surface areas.

In Fig. 12 the apparatus is shown as applied to the heat treating or drying of a ladle. The ladle is shown as comprising a suitable metallic vessel 50 with a ceramic, fire clay or brick lining 51, which is to be heat treated and dried. Inasmuch as the freshly applied ceramic may contain moisture or other volatile substances, the function of drying the same is substantially the same as that of drying molds and the above description applies. In this case, however, no nozzles for directing the air are needed because the entire surface is to be treated and there are no cavities or recesses in which the recirculating air need be directed. In addition to the drying the lining substance may be suitably heat treated for desirable time periods and temperatures.

In Fig. 13 a work piece 52 which may be a casting of metal or a forging or die or other item, is disposed in a container 53 and the heating unit 1 is placed on the container. In this case, there may not be any drying function but the work piece is subjected to the heat treating action for purposes as desired. Some work pieces may be normalized or tempered in this manner. In each instance, as shown in Figs. 12 and 13, the ladle or container or crucible 53 may be of circular shape and the heating units may be formed to properly fit and close upon the circular upper surface thereof.

I claim:

1. An apparatus for drying a mold for foundry which comprises, a housing-like body member adapted to be placed on the mold container, said body member having a heat insulating partition for providing a substantially closed chamber, a dividing wall spaced from the partition and positioned to be next adjacent the surface of the mold, and spaced from the surface of the mold, a fan in the chamber positioned between the partition and the dividing wall for circulating the gaseous contents in the chamber, heating means adjacent the fan for heating the circulating gaseous contents, a motor located on the side of the partition opposite the heating means for operating the fan, and a plurality of directing nozzles in said dividing wall which are adjustable for the directing of the circulating gaseous contents against and into the recesses in the surfaces of the mold material.

2. An apparatus for drying foundry sand mold while in a container, comprising a housing-like body adapted to be placed upon the container over the mold, a partition extending across the housing substantially in the mid-portion thereof and including a layer of heat insulating material, a dividing wall positioned so that it is spaced from the partition and from the surface of the mold to form an upper chamber and a lower chamber, an air fan in the upper chamber, electrical heating means in the upper chamber, an electric motor above the partition for driving the fan, a plurality of adjustable air nozzles in the dividing wall so that air moved by the fan is exhausted through the nozzles and upon the mold and into recesses thereof, said body being of rectangular form, and connecting means on the body arranged so that a plurality of like bodies with similar connecting means may be detachably connected together to form a multiple unit adapted to be placed over mold containers of relatively large size.
3. An apparatus for drying foundry sand mold while in a container comprising, a housing-like body adapted to be placed upon the container over the foundry sand mold, a heat insulating partition extending across the mid portion of the housing, a dividing wall positioned so that it is spaced from the partition and from the surface of the mold to form an upper chamber and a lower chamber, said body member resting upon the container so that the lower chamber is substantially closed to prevent escape of gases from the lower chamber and is not sealed tight so that gases may escape only under pressure, a fan in the upper chamber, an electric motor above the partition for driving the fan, heating means in the upper chamber for heating the gaseous contents moved by the fan, a plurality of adjustable air nozzles in the wall through which the gaseous contents propelled by the fan are discharged into the lower chamber, said nozzles being adjustable to direct the gaseous contents against and into cavities in the mold, a central opening in the dividing wall for the flow of gaseous contents from the lower chamber back to the upper chamber, whereby gaseous contents are circulated and recirculated by the fan in the drying of the mold.
